UNITED STATES PATENT OFFICE.

SAMUEL CLELAND DAVIDSON, OF BELFAST, IRELAND.

APPARATUS FOR DRYING TEA, HOPS, SLICED FRUITS, &c.

SPECIFICATION forming part of Letters Patent No. 416,157, dated December 3, 1889.

Application filed February 14, 1889. Serial No. 299,893. (No model.) Patented in England September 5, 1888, No. 12,844.

To all whom it may concern:

Be it known that I, SAMUEL CLELAND DAVIDSON, of Belfast, Ireland, a subject of the Queen of Great Britain and Ireland, have invented certain new and useful Improvements in Apparatus for Drying Tea, Coffee, Cocoa, Cinchona, Hops, Sliced Fruits, Seeds, Meal, or other such Substances, (for which I have obtained a patent in Great Britain and Ireland, No. 12,844, bearing date September 5, 1888,) of which the following is a specification.

The object of this invention is the construction of an apparatus in which a very strong current of heated air or cool desiccated air can be used for rapidly drying tea, coffee, cocoa, cinchona, hops, sliced fruits, seeds, meal, or other such substances, on sieves or perforated trays arranged in a drying-chamber one above the other in a vertical column, and movable in successive order of rotation from bottom to top of the column without the material being whirled by the strength of the current into heaps on the trays while in the drying-chamber, or blown away off them by it when the trays are being put into or taken out of the apparatus.

The present improvements consist in the construction of the apparatus for carrying out this object.

In the accompanying drawings, Figure 1 is a front elevation; Fig. 2, a vertical section on line 1 1 of Fig. 1; Fig. 3, a horizontal section on line 2 2 of Fig. 1, the fan box or case not being in section; and Fig. 4, a vertical section on line 3 3 of Fig. 3 of an apparatus constructed according to my invention in its preferred form. In this modification an exhaust-fan is employed to produce the current of air down through the trays. The device for temporarily checking or diminishing the draft when any of the trays are being inserted or withdrawn consists of a throttle-valve, and is fitted to the outlet or exhaust port from the drying-chamber, and a lift arrangement for moving up all the trays simultaneously and pawls for retaining them when moved up are provided. Fig. 5 is a vertical section showing a modification in which a gridiron-valve is employed in place of the throttle-valve. Fig. 6 is a section taken at right angles to the section of Fig. 5.

Referring first to Figs. 1 to 4, A is the drying-chamber.

B is the inlet-port for the heated or desiccated air.

C is the air outlet or exhaust. This, as shown, is made of a sheet-iron chamber projecting from the fan-opening in the side of the chamber A into the space below the trays, and has a rectangular opening or port C², into which a throttle-valve D is fitted.

T are the sieves or perforated trays. Each of these is fitted with carriers U U for supporting the tray next above.

P is a doorway or tray-port opposite the lowest tray for the insertion of the trays, and R is a similar doorway or tray-port opposite the topmost tray for the withdrawal of the trays. Each of these tray-ports is fitted with a door for closing same, (marked, respectively, Q and R².)

L L are vertical bars or lifters for moving up the pile of trays simultaneously. These bars or lifters are operated by means of the hand-lever G, which is centered on the shaft or spindle H, on which spindle are mounted beam-levers J J. These beam-levers at one end act directly upon the bars or lifters L L at the back of the apparatus, and simultaneously, through the intermediation of other beam-levers K K, upon the bars or lifters L L at the front of the apparatus.

O O are guides for the bars L L.

M M are pawls or catches, which support the lowest tray T when this has been pushed up by the bars L L. These pawls are moved aside by the tray as it is being pushed up; but when the tray has passed them they immediately drop in by reason of their own weight and support it. Instead of the weight of these pawls being depended upon to insure their dropping into position, they may be fitted with springs M², as shown in vertical and horizontal sections, respectively, in Figs. 5 and 6.

G² is a segmental catch-bar for holding the lever G in the required positions.

N N are angle-iron rails or slides for the bottom tray when first inserted.

N² N² are angle-iron stops to prevent the trays being lifted past the upper tray-port R.

F is a lever fitted on the shaft H and connected by a link F⁴ to the throttle-valve D.

Thus as the shaft H turns when operated on by the lever G, so as to open the lower tray-port door Q to let in a fresh tray and lower the lifting-bars L L to receive this tray, the valve D is caused to close against the top and bottom portions C³ C⁴ of the exhaust-chamber C. The top portion C³ serves as a chute to guide to the middle of the drying-chamber any material that may fall through the trays. The spindle of the valve D turns in bearings C⁵ C⁶ in the sides of the exhaust-chamber.

Q is the door of the lower tray-port P. It is attached to the lifting-bars L L and moves therewith.

S is the exhaust-fan.

V is a door to allow of the removal, when necessary, of any of the intermediate trays.

W is a door for giving access to the base 20 of the drying-chamber.

The operation of the apparatus is as follows: When a tray has to be inserted, the lever G is moved so as, through the intermediation of the beams J J and K K, to lower the bars L L, the same movement having the effect of opening the door Q, and, through the intermediation of the lever F and link F⁴, of closing the valve D. The tray is then inserted through the tray-port P. The lever G is then returned to its first position, whereby the bars L L are raised, so as to lift the tray (with all others that are above it) to close the door Q and to open the valve D. The tray passes the pawls M, and these then drop under 35 the tray, so as to support it. The same operation is repeated at the insertion of every following tray, it being of course understood that if the chamber contains its full complement of trays the topmost one must be withdrawn through the tray-port R before another is inserted through the tray-port P.

The air-current down through the trays may be produced by pressure-blast with fans or other suitable blowing apparatus, and on 45 being driven into the air-space above the top tray it will of course find its way down through the trays to the outlet-port; but the current is preferably produced down through the trays by exhausting the air from below 50 the trays by means of an exhaust-fan S, as shown, or by a suitable air-pump; or a powerful chimney-draft can be connected to the outlet-port. The air may be heated by any suitable air-heating appliances—such as an 55 air-heating stove or steam-pipes or pipes heated directly by fire; or cool desiccated air may be used, and its desiccation may be effected by any suitable desiccating operation—such as passing it over dry chloride of lime 60 before being admitted to the drying-chamber. The course of the air-current being down through the trays from top to bottom of the drying-chamber, it is obvious that, no matter how strong the current may be, it cannot disturb or blow the material about on the trays 65 while they are in proper position within the chamber, as the stronger the current the more

firmly is the material held in its place on the trays, whereas were the current upward through the trays it would lift the material 70 or whirl it about into heaps upon them; but while the trays are being inserted or withdrawn there would be, when means are not taken to prevent it, such a strong indraft through the bottom tray-port when the air-current is being produced by an exhaust 75 from below the bottom tray or outdraft through the top tray-port, if it is produced by a pressure-blast delivered above the top tray; that the rush of air would be so strong that 80 the material on the trays would be blown off them. It is for this reason that I employ a valve or appliance, as hereinbefore described, for temporarily checking or diminishing the draft or current while the trays are being inserted or withdrawn from the apparatus. 85

Referring now to the modification shown in Figs. 5 and 6, D is the gridiron-valve employed in lieu of the throttle-valve in Figs. 1 to 4. This valve is operated from one of the 90 lifting-bars L through the intermediation of the rod F and bell-crank F⁴.

What I claim, and desire to secure by Letters Patent, is—

1. In an apparatus for drying substances 95 by means of a strong down draft or current of heated air or cool desiccated air, the combination of a drying-chamber, a column of perforated trays in said chamber, a tray inlet-port at the bottom of said column, a tray outlet-port at top of said column, doors to said inlet and outlet ports, an inlet for the current of air at the upper end and an air outlet or exhaust at the lower end of said chamber, a valve or damper fitted to said air-outlet for temporarily cutting off or diminishing the air current or draft when any of the trays are being inserted or withdrawn, and a connection, substantially as described, between the valve or damper and the door of 100 the tray inlet-port, whereby when said valve or damper is open the said door is shut, and vice versa, substantially as and for the purpose set forth.

2. In an apparatus for drying substances 115 by means of a strong down draft or current of heated air or cool desiccated air, the combination of a drying-chamber, a column of perforated trays in said chamber, a tray inlet-port at the bottom of said column, a tray 120 outlet-port at the top of said column, doors to said inlet and outlet ports, an inlet for the current of air at the upper end and an outlet or exhaust at the lower end of said chamber, a valve or damper fitted to the said air-outlet for temporarily cutting off or diminishing 125 the air current or draft when any of the trays are being inserted or withdrawn, bars or lifters for raising all the trays simultaneously, pawls or catches for supporting the trays 130 when raised, and an appliance, substantially as described, for simultaneously operating the valve or damper, the door of the tray inlet-port, and the bars or lifters, the valve or

damper being open when the door of the tray inlet-port is shut and the bars or lifters are raised, and vice versa, substantially as and for the purpose set forth.

- 5 3. In an apparatus for drying substances by means of a strong down draft or current of heated air or cool desiccated air, the combination, with the drying-chamber A, movable sieves or perforated trays T within said chamber, air-inlet B at the upper part of said chamber, exhaust-outlet C at the lower part of said chamber, valve D, controlling said outlet, and fan S, of the bars or lifters L, for raising said trays, pawls or catches M, for supporting said trays when raised, and the pivoted lever G, said lever being connected to said valve and to said bars or lifters, substantially as and for the purposes set forth.
4. In an apparatus for drying substances by means of a strong down draft or current of heated air or cool desiccated air, the combination, with the drying-chamber A, movable sieves or perforated trays T within said chamber, air-inlet B at the upper part of said chamber, exhaust-outlet C at the lower part of said chamber, fan S, bars or lifters L, for raising said trays, pawls or catches M, for supporting said trays when raised, and pivoted lever G, for operating said valve and said bars or lifters, of the shaft H, carrying said lever, beam-levers J J and K K, connecting said shaft and said lifters L, lever F, and link F⁴, connecting said shaft and said valve D, substantially as and for the purpose set forth.
- 35 5. In an apparatus for drying substances by means of a strong down draft or current of heated air or cool desiccated air, the com-

bination, with the drying-chamber A, movable sieves or perforated trays T within said chamber, air-inlet B at the upper part of said chamber, exhaust-outlet C at the lower part of said chamber, valve D, controlling said outlet, bars or lifters L, for lifting said trays, and pawls or catches M, for supporting said trays, of an upper tray-port or doorway R in the upper part of said chamber, lower tray-port or doorway P in said chamber, and a door Q to said port P, said door being attached to the front bars or lifters L, so as to move therewith and to close the port when said bars are lifted, substantially as and for the purpose set forth.

6. The combination, substantially as described, of the drying-chamber A, air-inlet B thereto, exhaust-outlet C therefrom, fan S, valve D, controlling said outlet, trays or sieves T within said chamber, tray inlet-port P, door Q of said inlet-port, tray outlet-port R, door R² thereof, bars or lifters L, for raising said trays and connected with said door Q, pawls or catches M, for holding said trays when raised, lever G, notched segmental bar G², coacting with said lever, shaft H, to which said lever is secured, beam-levers J and K, connecting said shaft H and lifters L, lever F, and link F⁴, connecting said shaft H and valve D, substantially as and for the purposes set forth.

In witness whereof I have hereunto signed my name in the presence of two subscribing witnesses.

SAMUEL CLELAND DAVIDSON.
